UNITED STATES PATENT OFFICE.

EDWARD JOSEPH HILL, OF PHILADELPHIA, PENNSYLVANIA.

LIFTING DEVICE.

Application filed September 1, 1921. Serial No. 497,545.

To all whom it may concern:

Be it known that I, EDWARD JOSEPH HILL, a citizen of the United States, residing at Philadelphia, in the county of Philadelphia 5 and State of Pennsylvania, have invented certain improvements in Lifting Devices.

The object of this device is to provide a clean and easy means for raising a box or basket of ashes or the like from the level of the cellar floor to the level of the cellar window and lifting it so that the effort required is much less than is the case when they are lifted by hand and so that the job can be done without getting dirty as is ordinarily the case.

I attain these objects by the means shown in the accompanying drawing and described in the annexed specification.

The drawing shows the ash lifter in perspective and in a partly raised position.

Referring to the drawing, 1 is the base upon which the device stands. Pivoted to the said base by the hinge 2 is the leg 3 which is pivoted at its upper end to the platform 4 by means of the hinge 5. At each side of the base 1 is pivoted the legs 6 and 7 by means of the bolts 8 and 9. These legs are also pivoted to the sides of the platform 4 by means of the bolts 10 and 11 and are provided with the grips or handles 12 and 13 by means of which the apparatus is operated. The legs 3, 6 and 7 are provided with means by which the platform 4 may be adjusted to different heights. The leg 3 is provided with a sleeve 14 which telescopes over it and the two parts are connected together by means of the bolt 15 which passes thru the holes 16. Adjustment of the legs 6 and 7 is made by putting the bolts 10 and 11 in one of the holes 17.

The device is placed on its base 1 on the cellar floor with the legs 3, 6 and 7 laid down parallel to the floor and at right angles to the wall beneath the window. This brings the platform 4 almost down to the floor, an ash box or basket is then placed on the platform 4 and the handles 12 and 13 are grasped and lifted. At the beginning of the lift the operator raises somewhat less than the full weight of the ashes and at this point this is very easy to do on account of the mechanical advantage obtained by the leverage which more than compensates for the weight of the device and as the platform is raised the effort required for lifting becomes less until when it reaches the top the lift is zero.

As shown in the drawing the adjustment for the height of the platform 4 is made, in the case of the legs 6 and 7, by placing the bolts 10 and 11 in different holes in said legs, 60 and in the case of the legs 3, by means of the sleeve 14 and a bolt passing thru both, but it is evident that all three legs could be provided with a sleeve similar to that on leg 3 for purposes of changing their length without departing from the scope of this invention.

I am aware that devices have been made previously which raise a platform while said platform remains horizontal, and I therefore 70 do not claim such a means broadly but I claim:

1. The combination of a base adapted to rest on the floor or the like, two tubes or rods pivoted by their lower ends to said base, one 75 to each side; a third tube or rod pivoted by its lower end to another point of said base, which performs a function similar to the first named two tubes or rods, said third tube being provided with a series of holes 80 along its length; a sleeve provided with a hole at its lower end to match holes in said third tube, said third tube being adapted to slip into said sleeve; a pin or bolt adapted to engage said hole in said sleeve, and one 85 of said holes in said third tube and to lock said sleeve and said third tube together, a platform pivoted to the upper end of said sleeve and to intermediate points on the first named two tubes or rods and grips attached 90 to said tubes or rods at their upper ends with which to raise said platform relative to said base through the medium of the three tubes or rods.

2. The combination of a base adapted to 95 rest on the floor or the like, two parallel members pivoted to said base at their lower ends, a third member parallel to said first named members pivoted to another point of said base, a platform pivoted to the upper 100 end of said third member and to an intermediate point of said first named parallel members, grips attached to said first named parallel members for raising said platform relative to said base thru the medium of said 105 three members and means for adjusting the relative positions of said platform and said base.

3. The combination of a base adapted to 110 rest on the floor or the like, three members pivoted to the said base at their lower ends, two of said members being pivoted to the

sides of said base and the third being pivoted to that side of said base nearest the operator of the device; grips for operating the device attached to the said two side members and means for varying the height of said platform relative to said base.

4. The combination of a base adapted to rest on the floor or the like, two long side members pivoted at their lower ends to said base and parallel to each other, grips or handles attached to the upper ends of said side members whereby the device is operated, said grips being placed at right angles to said side members; a platform pivoted to points on said side members intermediate the grips and the base, a third member parallel to said side members and pivoted to

said base and said platform and means for varying the distance between said platform and said base.

5. The combination of a base adapted to rest on the floor or the like, two long side members pivoted at their lower ends to the sides of said base and provided at their upper ends with grips or handles, a third member pivoted at its lower end to a point nearer the operator than the said side members, a platform pivoted to the upper ends of said third member and to intermediate points on said side members so that all three members are at all times parallel and means for varying the relative distance of said platform and said base.

EDWARD JOSEPH HILL.
